TROUSERS AND METHOD OF FORMING
SAME

David M. Dean, Detroit, Mich.

Application October 18, 1935, Serial No. 45,628

4 Claims. (Cl. 2—227)

This invention relates to wearing apparel and has particular reference to a method of drafting and manufacturing trousers. An object of the invention is the provision of an article of the nature referred to, which has an elastic section in the back stride.

The present method of manufacturing trousers and overalls is based upon exact scientific studies which I do not propose to discard in my new 10 method. I merely add to and improve the old method. Trousers are generally cut to the requirements necessary to create a well fitting garment when the wearer is standing. In a sitting position, however, the natural expansion of 15 the seat and thigh causes a constriction at the front waist line and a pronounced pull at the back waist line and at the stride. Two things are usually done in an attempt to lessen this unfortunate condition. In the drafting operation, 20 plus material is provided in the back stride to permit sitting and stooping; and to give the trousers a smooth hanging appearance when in a standing position, steam and hot irons are applied to the back stride to stretch it into shape. 25 This, however, removes all elasticity from the material at the points which receive the greatest strain when the wearer is sitting and stooping. Since the waist line of the trouser is fastened close to the body above the hip bone, a sitting 30 position results in discomfort and agony for the wearer, and in a breaking down of the material in the back stride due to the excess strain at that point. This premature wear in the back stride considerably shortens the life of the garment. 35 Another disadvantage of the present method is that sitting and stooping movements cause the knees to "bag" soon after pressing, due to the strains and distortions produced in the material.

I propose to eliminate the above mentioned disadvantages, and others, by my new method of drafting and manufacturing trousers.

One of the principal objects of my invention is to manufacture trousers which will be comfortable to wear, both in standing and sitting 45 positions.

Another object of the invention is to prolong the life of the trousers by reducing excess wear in the seat and back stride. This additional wearing quality will make it unnecessary to purchase two pairs of trousers with each suit, thereby effecting a large saving.

An advantageous feature of the invention resides in the improved appearance of the trousers, for the reason that they will conform to the body, 50 lines and will hang better. The customary distor-

tion and wrinkling of the material when the wearer is sitting will be appreciably reduced and the trousers will hold a press longer.

Another advantageous feature of my method resides in the saving of material effected by the 5 new drafting outline, especially in the manufacture of riding breeches and the like. This saving will offset the expense of adding my improvement.

A further object of the invention is the incorporation of my improvement in the general system of trouser drafting and manufacture without materially changing said system.

Another object of the invention is the provision of a method adaptable to all kinds of materials 15 and textures, and to all types of trousers.

A still further object of the invention is the reduction of the cost and labor necessary in making alterations.

Other objects and advantages of the invention 20 will appear as the description proceeds.

The invention resides in the improved construction of trousers, and in the combination and arrangement of parts, the novelty of which will be particularly pointed out and distinctly claimed 25 hereinafter.

In the accompanying drawing, which constitutes part of my disclosure, I have fully and clearly illustrated a preferred embodiment of the invention, in which drawing:

Fig. 1 is a side elevation of the rear half of a 30 trouser leg, and illustrates my improvement in the back stride.

Fig. 2 is a smaller side elevation of the rear pattern of a trouser leg for incorporating my improvement, and shows the saving of material 35 effected thereby.

Fig. 3 is an enlarged fragmentary plan view of the seam between two pieces of material embodying my improvement, for example, at the back 40 stride of trousers.

Fig. 4 is a cross section taken on line 4—4 of Fig. 3.

Referring now more particularly to the drawing, Fig. 1 illustrates the rear half of a trouser leg, ready to be sewed to the other pieces (not shown) which comprise a finished pair of trousers. The portion 7 of the material 8 is generally known as the back stride, and is the part which 45 receives severe strain when the wearer is in a sitting or stooping position. I propose to improve the construction of the back stride 7 to enable it to "give" or stretch with the bending of the body, 50 at the same time maintaining a perfect fit when 55

the wearer is standing. This I prefer to accomplish by the means to be hereinafter described.

The pattern is so cut as to provide an excess of material in the back stride 7, as indicated by the dotted lines 9 (Fig. 1). A resilient member 10, which may be a strip of rubber or any other suitable material, is stretched a predetermined amount from its normal position and sewed in its elongated form along the back stride 7.

- 10 The member 10 is positioned a slight distance back from the edge of the material 8, forming a narrow strip of cloth 11 which may be used as a hem when the various pieces of the trousers are stitched together. When the tension which has been placed on the resilient member 10 during the sewing operation is released, the member 10 resumes its normal length, pulling the cloth in the back stride 7 with it. The back stride 7 is now in the form indicated by the numeral 12, 15 in which position it is pressed into a smooth shape by a pressing machine or any other suitable means.

In outward appearance to the naked eye the material in the back stride 7 is the same as the material 8 in the rest of the garment. Actually, however, the strands of thread are closer together, that is, the pores in the weave are compressed into smaller form. It is easily seen that the material is not harmed in any way.

- 30 In its normal form the back stride 7 is correctly proportioned to fit perfectly when the wearer is standing. In a sitting position, however, the resilient member 10 stretches to accommodate the enlarged seat and thighs and again fits the wearer perfectly, without discomfort to him. The material in the back stride 7 also stretches with the member 10, but because of its previously compressed state it does so without strain or wear of the fibers.

- 40 The many advantages of my improved trouser construction are readily seen from the above description and the drawing referred to.

I do not wish to limit my invention to any particular pattern of the material or to a particular position of the resilient member 10, it being within the contemplation of the disclosure to vary the draft and the disposition of the resilient strip as desired by the designer. Likewise, the size of the resilient member and the amount of stretch incorporated therein, may vary with the material used and the type of garment.

One possible and preferred means of applying my method is shown in Fig. 2 and hereinafter described. By proper manipulation of the back pattern of trousers a surplus of material may be obtained in the back stride and later pulled into a compressed form by a resilient member, as described above.

- 60 In Fig. 2, line 13 is the center line of the back pattern, 14 the waist line, 15 the seat measurement line, 16 the crotch draft line and 17 the seat draft line. Proper manipulation of the pattern gives a back stride 18-19 which contains a surplus of material as compared to the back stride 20-21 of the old pattern, the latter being shown in dotted lines. This surplus material is only needed in a sitting or stooping position and for a normal standing position is taken up by an elastic strip placed along the back stride, as hereinabove described with particular reference to Fig. 1. A study of Fig. 2 will show how a large

amount of material may be saved by drafting the back pattern to adapt it to my improvement in the back stride.

In present practice it is necessary to cut the portion above line 17 (Fig. 2) on the bias, in order to give sufficient room when the wearer is walking, sitting or stooping, and still maintain the weave line of the fabric parallel with the crease line 13. In my method it is not necessary to cut the material at so acute an angle, therefore, I effect a saving of material as defined by the dotted line 13a.

The only change in the process of manufacturing trousers necessary to embody my improvement therein is the insertion of an elongated resilient member along the back stride and the pressing of the material in the aforesaid back stride. The back pieces of the trousers are then stitched together as in the conventional method. A fragmentary view of such a seam is shown in Figs. 3 and 4; wherein the pieces 8 and 8a, to which the resilient members 10 are fastened, are brought together and stitched at the seam 22. The pieces 8 and 8a are turned over the resilient strips 10 and hemmed as at 23 (Fig. 4).

It is also within the contemplation of the invention to apply my novel combination of an elastic member and a compressed material to other uses, such as seams in other garments, etc.

Although I have herein disclosed a certain embodiment of the invention, it will be understood that various modifications may be employed, without violating the spirit of the invention, for example, in some instances, I will weave elastic threads into the fabric along the stride, all of which is intended to be within the scope of the appended claims.

Having described my invention, what I claim and desire to secure by Letters Patent is:

1. The combination with a garment having leg portions consisting of front and back sections, there being an excess of material in said back section, of a narrow elastic member secured adjacent to and parallel with the edges of the stride portion of said back section.

2. In a garment having leg portions made of front and back sections, the latter being formed with an excess of material in the stride portion, the combination of a strip of elastic material, secured within a hem adjacent to and parallel with the edges of the stride portion of said back section.

3. The method of making a garment having leg portions which consists of forming front and back sections according to a predetermined pattern, allowing an excess of material along the stride portion of each back section, securing elastic members, while in extended condition, adjacent to and parallel with the edges of said stride portions, and then securing together said front and back portions.

4. The method of making trousers which consists of cutting front and back sections according to a predetermined pattern, so that each back section has a surplus of material at the stride, compressing said surplus material to a second predetermined pattern, by securing along the edges of said stride, elastic members while the latter are in extended formation, and then securing together the longitudinal edges of said front and back sections.

DAVID M. DEAN.
